UNITED STATES PATENT OFFICE.

PATRICK H. FINNEGAN, OF CRESO, IOWA.

FENCE-WIRE STRETCHER.

1,390,770.

Specification of Letters Patent. Patented Sept. 13, 1921.

Application filed November 13, 1920. Serial No. 423,774.

To all whom it may concern:

Be it known that I, PATRICK H. FINNEGAN, a citizen of the United States of America, residing at Cresco, in the county of Howard 5 and State of Iowa, have invented new and useful Improvements in Fence-Wire Stretchers, of which the following is a specification.

The object of the invention is to provide a simple, inexpensive and efficient stretcher 10 for fence wires of the barbed or plain type wherein an interchangeable location of the draft from one side of a post to the other may be readily effected, and whereby the stretched length of the wire is disposed in 15 proper relation to the plane of the post which is being used as an anchor for the stretcher so as to facilitate the stapling of the wire to retain the tension which has been applied thereto by means of the stretching 20 apparatus and to this end the invention consists in the construction and combination of parts of which a preferred embodiment is illustrated in the drawings, wherein:—

Figure 1 is a plan view of the apparatus. 25 Fig. 2 is a side view of the same. The device consists essentially of a shank 10 with which at an intermediate point is connected a bearing arm 11 for engagement with a post as indicated at 12, said bearing 30 arm having in connection therewith a retainer 13 consisting for example of a chain for encircling and gripping the post, a link at or near the free end of the chain being engageable as indicated at 14 with the free 35 end of the arm; and stretcher mechanism including a drum 15 mounted upon the shank in rear of the bearing arm to the end that the stretched portion of the wire which is indicated by dotted lines at 16 in Fig. 1 shall 40 be disposed in proximity to and tensional relation with the post so that staples engaging the stretched portion of the wire may readily be driven into the post to hold the tension which has been applied to the 45 wire.

The bearing arm is connected with the shank of the stretcher by means of a clamp 17 secured in place by a bolt 18 to the end that the bearing arm may be extended in 50 either direction horizontally from the shank to dispose the shank at either side of the post to suit the fence wires or strands being extended for attachment to the post.

The drum 15 is peripherally grooved to 55 receive the wire and is provided with ratchet teeth 19 for engagement by a pawl 20 car-

ried by an operating lever 21 fulcrumed concentric with the drum, a suitable grip lever 22 pivotally mounted as at 23 upon the operating lever being connected by a rod 24 60 with the pawl to enable the latter to be engaged with or disengaged from the ratchet teeth as the operation of applying tension to the fence wire or strand progresses.

In connection with the drum, for retaining the tension applied thereby to the fence wire or strand there is employed a gripper consisting of jaws 25 pivoted as at 26 upon a cross head 27 of the shank and having serrated engaging faces 28 between which the fence wire or strand extends. The frictional contact of the wire or strand passing between the jaws of the gripper will serve under ordinary conditions to maintain the jaws in engaging relation with the wire, but in addition thereto springs 29 will be employed as shown, said jaws having upstanding ears 30 to facilitate the disengagement thereof from the wire or strand after the completion of the stretching operation and 80 the stapling of the wire to the post.

At the extreme forward end of the shank there is preferably provided a wire guide 31 which serves to maintain the shank in alignment with the wire or strand to which tension is being applied.

To facilitate an interchangeable or selective arrangement of the bearing arm at either side of the shank to provide for stretching a fence wire or strand in a plane 90 at either side of the post, the shank is preferably tapered from the point of engagement of the clamp 17 therewith to the end carrying the guide 31, so that the clamp may be readily slid longitudinally from the shank 95 and replaced in a position adapted to suit the preferred arrangement of the device with reference to the post, said clamp in effect serving as a sleeve removably fitted upon the reduced or tapered portion of the 100 shank, and the movement of the shank with reference to the sleeve and bearing arm, when properly engaged, being prevented by an enlargement or shoulder 32 on the shank bearing against the ear 33 on the inner end 105 of the bearing arm 11. Said ear is forced into contact with the surface of the shank by the rearward pressure applied to the arm by the post, so that in operation the parts are in effect located in their proper relations where- 110 as upon the release of strain upon the fence wire or strand and the tilting of the arm

11 upon the pivot bolt 18, the engagement of the sleeve or clamp 17 is relieved sufficiently to permit of the free sliding movement of the latter upon the shank.

5 Having described the invention, what is claimed as new and useful is:—

1. A fence wire stretcher having a shank provided intermediately of its length with a transverse bearing arm for contact with a post, and having terminally arranged wire stretching and guiding means, said bearing arm being selectively attachable to the shank at either side thereof.

15 2. A fence wire stretcher having a shank provided intermediately of its length with a transverse bearing arm for contact with a post, and having terminally arranged wire stretching and guiding means, said bearing arm being selectively attachable to the shank at either side thereof and provided with a clamp for detachably engaging said shank.

20 3. A fence wire stretcher having a shank provided intermediately of its length with a transverse bearing arm for contact with a post, and having terminally arranged wire stretching and guiding means, said bearing arm being selectively attachable to the shank

30 at either side thereof and provided with a clamp for detachably engaging said shank, and shank being tapered from the plane of said clamp to the guide-carrying end thereof.

35 4. A fence wire stretcher having a shank provided intermediately of its length with a transverse bearing arm for contact with a post and having terminally arranged wire stretching and guiding means, a cross head mounted on the shank adjacent the stretching means and carrying a gripper for engaging and maintaining the tension of the 40 stretched wire, the shank having an enlargement adjacent the cross head to provide a shoulder for abutting engagement by an ear on the bearing arm, and a clamp straddling the shank and engaging the bearing 45 arm, whereby the bearing arm is rendered selectively attachable at either side of the shank, the latter being tapered in the direction of its length from the said enlargement to the terminal guiding means.

50 In testimony whereof I affix my signature.

PATRICK H. FINNEGAN.
